PRINTING AND EMBOSSED DIE

Fred Weindel, Jr., and Wilbur F. Price, Allentown,
Pa., assignors to L. F. Grammes & Sons, Inc.,
Allentown, Pa., a corporation of Maryland

Application October 14, 1932, Serial No. 637,676

3 Claims. (Cl. 101—201)

This invention relates to printing and embossing dies of a kind useful more particularly in the production of multicolor cards or labels from sheet materials such as paper-backed metal foil.

5 Dies of the kind referred to ordinarily consists of several printing sections to take the different colors, these sections being relatively movable so that the printing or type face of one may be brought above or below the printing or type 10 faces of the others to enable selective application of the colors preparatory to making each impression. For the production of two color labels, for example, the construction of the dies has been such heretofore, as to restrict placement 15 of the different colors, with consequent limitation in the design or decorative variations which could be obtained. In other words, with the usual type of dies embodying, say a main die section, and a secondary die section movable in 20 said main section as and for the purpose explained, it was impossible to print the color relegated to the main die section within the area printed in another color by the secondary die section, or to print the color of the secondary die 25 section in different portions of the area printed by the primary die section without resorting to stagewise printing.

Our invention is directed toward overcoming the recited drawbacks in multicolor label printing and to make possible the production, by single impressions, cards or labels characterized as above explained, which end we attain as fully explained in the detailed description which follows of the attached drawing, wherein Fig. I 35 shows a cross sectional view through a printing and embossing die embodying our invention in one form.

Figs. II and III are fragmentary illustrations corresponding to Fig. I showing the different 40 positions to which the secondary section of our die is moved incident to inking of the die.

Fig. IV shows a label produced with the die of Figs. I-III.

Figs. V, VI and VII are views like Figs. I-III 45 showing another form of our novel printing and embossing die; and

Fig. VIII shows a label produced with the die of Figs. V-VII.

Referring first more particularly to Figs. I, II 50 and III of these illustrations, the numeral 10 designates a die block constituting a part of a printing machine, and the numeral 11 a surmounted printing and embossing die embodying our invention in one form for producing the two-color label of Fig. IV. As shown, the die 11 com-

prises an integrally formed main section 12, and a secondary section 13, which, in this instance is annular and occupies a correspondingly configured central recess 14 in said main section with capacity for being moved up and down 5 therein. The outer type ridge 15 of the main die section 12 prints the outlining figure or border A of the label of Fig. IV, and the inner ridge 16 prints the infield or center B of said label both of the same color, e. g. blue; while the type 10 face 17 of the secondary die section 13 prints an annular area C of a contrasting color, e. g. red, around the infield or center B. The unshaded portions D, E and F of the label show the natural color of the metal foil (e. g. brass) 15 forming the base of the label, by virtue of the depressions 18 between the ridges 15 and 16 of the main die section 12. In order that the label may be cut from the stock foil concurrently with 20 its printing, the main die section 12 is formed 25 with a continuous perimetric cutting edge 19.

In the use of the die of Figs. I-III, the blue ink is first applied by a roller or pad of the printing machine to the ridges 15 and 16 of the main die section 12 at a time when the annular secondary die section 13 is depressed in the recess 14 of said main die section as shown in Fig. II. With this accomplished, the secondary die section 13 is raised, as shown in Fig. III, so that its printing face 17 is above the level of the ridges 30 15 and 16 of the main die section 12, and the red ink applied thereto by another of the color pads or rollers (not shown) of the printing machine. Thereupon the secondary die section 13 is lowered until its printing face 17 is flush with 35 the type ridges 15 and 16 of the main die section 12, as in Fig. I, in readiness for a printing operation. The base sheet (not shown) for the label is then finally placed on the die 11 and pressed into contact therewith in the usual and well 40 known way to receive the impressions, and incidentally blanked by the severing edges 19 of the main die section 12. In the illustrated instance the secondary die section 13 is connected to the vertically reciprocating plunger 20 of the 45 printing machine by projections in the form of dowel pins indicated at 21 which extend through correspondingly allocated apertures in the main section 12; and the center portion of the main section 12 is supported and braced by a bridging 50 piece 22 lying crosswise of the guide opening 23 for said plunger in the die block.

From the foregoing it will be seen that with a die constructed according to Figs. I-III, it is possible to produce, in one operation, ornamental 55

labels or cards wherein portions of one color lie within, as well as beyond portions of another color.

In the form of our improved printing and embossing die shown in Figs. V-VIII, there are two secondary sections 13a and 13b which are movable up and down in openings 14a and 14b respectively in the main section 12a, said secondary sections being here directly secured to the plunger 20a of the label printing machine. The ridges 15a of the main die section 12a in this case, define, as shown in the label of Fig. VIII, an outlined arrow A with a diamond at the center of its shaft in blue; while the secondary die sections 13a and 13b define solid red areas C' and C² respectively at the tail and head of the arrow. As in the first exemplification of our invention, the depressed areas of the die of Figs. V-VIII permit showing of the color of the metal foil in the areas E' and F' beyond and within the two-color figure produced in the label. Thus with the die construction of Figs. V-VII, the secondary color (in this instance red) can be placed at different points within the area of a figure produced by the primary color (blue).

The two different dies and labels herein featured are to be considered as illustrations merely of innumerable other designs which can obviously be predetermined by variant arrangement and formation of the main and secondary die sections. The number of secondary die sections can of course be increased in either case in accordance with the character of the ornamentation which is to be produced in the card or label.

Having thus described our invention, we claim:

1. A die of the character described, comprising

ing an integrally-formed main printing section with infield and outfield areas; a secondary printing section with an annular printing area for a different color continuously around the infield area of the main section and recessed into the latter with capacity for being moved in and out of the same to enable separate inking of the two sections; and an actuating member with projections extending through the back of the main section and connecting with the secondary section.

2. A die of the character described comprising an integrally formed main printing section with infield and outfield printing areas; a secondary printing section with an annular printing area for a different color continuously around the infield area of the main section and recessed into the latter with capacity for being moved into and out of the same to enable separate inking of the two sections; and an actuating member connected to the secondary section by a number of pins extending through guide apertures in the back of the main section.

3. A die of the character described comprising an integrally formed main section with raised areas to emboss and print outfield and infield areas; a secondary section with an annular printing area for a different color continuously around the infield area of the main section and recessed into the latter with capacity for being moved into and out of the same to enable separate inking of the two sections; and an actuating member with projections extending through the back of the main section and connecting with the secondary section.
